UNITED STATES PATENT OFFICE.

GEORG KIRKEGAARD, OF NEW YORK, N. Y., ASSIGNOR TO IMPERIAL STOPPER COMPANY,
A CORPORATION OF MAINE.

CAPPING-MACHINE.

No. 922,776.

Specification of Letters Patent.

Patented May 25, 1909.

Application filed May 6, 1908. Serial No. 431,147.

To all whom it may concern:

Be it known that I, GEORG KIRKEGAARD, a citizen of the United States, residing at the city of New York, in the borough of Brooklyn and State of New York, have invented certain new and useful Improvements in Capping-Machines, of which the following is a full, clear, and exact description.

This invention relates to bottle capping machines of that class which are adapted to apply a stopper to a bottle, comprising a metal cap having a depending flange adapted to making locking engagement with the exterior of the neck of the bottle and containing a packing disk which is held under compression against the mouth of the bottle by such locking engagement. In machines of this character, especially those which are driven by power, the stroke of the plunger 20 and head which applies the cap to the bottle is usually of uniform length and, if the bottle happens to be of abnormal length, as often occurs, unusual pressure is exerted upon the bottle by the machine, which results in breakage and loss.

It is the object of my invention to provide a machine which, while affording the necessary pressure to compress the packing disk and apply the cap, will automatically compensate for any unusual length in the bottle and prevent the breakage and loss referred to.

The invention consists in supporting the table upon which the bottle, while undergoing the capping operation, is supported, upon a spring having a tension sufficient to resist the pressure of the machine when acting upon a bottle of normal size.

The invention further consists in providing a support or abutment for said spring which is adapted to yield or retreat under certain conditions, but which is normally held by a latch or equivalent means.

In capping a bottle of unusual length the latch is tripped and the support is allowed to retreat or recede, thus permitting the bottle to move with the stroke of the capping machine and relieve itself of the undue pressure which it would otherwise be subjected to.

The invention will be described in detail with reference to the accompanying drawings, in which—

Figure 1 is a vertical section of the machine with parts in elevation. Fig. 2 is a horizontal section on line α — α of Fig. 1,

looking downward, and Fig. 3 is a plan of a plate which supports the table.

Referring to the drawing by reference numerals, 1 indicates the base frame and 2 a hollow standard supported thereon. 3 is a continuously running pulley through which power is transmitted to the machine, and 4 is a treadle by which the moving pulley is coupled to the shaft 5 for each operation of the machine. The shaft 5 carries a crank 6 which is adapted to impart a stroke downward and upward to a rod 7 extending up through the hollow standard 2. This rod carries a capping head at its upper end 8, adapted to move in suitable guides 9 and 10 having proper mechanism at 10 for engaging the cap on the bottle and locking it under compression thereon. The pan 11 is merely a receptacle for stoppers. These features do not form any part of the present invention.

Against the front of the standard is bolted a plate 12 carrying a vertical cylinder 13, the lower end of which is closed, except for a threaded perforation which accommodates an adjusting screw 14 having a locking nut 15. The upper end of the cylinder is open, but serves as a guide for a table 16 having on its upper surface a cushion of rubber or other suitable material 17 upon which the bottle rests while being acted upon by the machine. The table is of sufficient length to be held steadily in the cylinder, and it is provided on its under side with an annular inclined surface 18 and with a central cylindrical projection 19.

The screw 14 sustains a horizontal disk or support 20 which may be adjusted vertically and locked at any point of adjustment by means of the screw and its locking nut. This disk is provided with a central upwardly projecting pin 21 and with three notches 22 equally spaced around its periphery. Above the disk 20 is another disk 23 having a central opening which enables it to be passed over the pin 21, and it is yieldingly sustained some distance above disk 20 by a spring 24. This disk is likewise notched around its periphery, and flanking each notch are upwardly-extending ears 25 in the upper ends of which are the pivot pins 26 of three levers 27. These levers extend downward and upward from their pivots, their lower ends normally resting upon disk 20 opposite the notches 22, and their upper ends carrying

rollers 28 which bear against the inclined annular surface 18 of the table 16. The lower end of each lever is provided with a spring 29 which bears against the wall of the cylinder 13 so as to move the lever inward when free to do so. The disk 23 serves as a support for a second spring 30 considerably heavier and stronger than the spring 24. This spring surrounds the upper end of pin 21 and the projection 19 of the table, the table being held in its normal position or elevation by this spring. Above the table at a proper elevation is a bracket carrying a yoke 31 which facilitates positioning the bottle upon the table.

The various parts are shown in their normal relation, wherein it will be seen that the supporting disk 23 is positively sustained at a fixed distance above the main supporting disk 20 by the levers 27, and the spring 21 is under no special compression due to the weight of the parts above it. The spring 30 is constructed to be of just sufficient power to sustain the bottle at approximately a constant level, yielding only when an extraordinary downward pressure is applied to the table, so that, in the ordinary operation of capping a bottle, the bottle is placed on the table in the position shown in Fig. 1, and the treadle 4 is actuated. The head moves downward and exerts considerable pressure in a downward direction against the top of the bottle to compress the packing disk in the cap and then lock the cap upon the bottle. If the bottle is of normal length, the spring 30 will sustain the table, allowing it to lower only slightly and not enough to cause the rollers 28 to travel on the inclined annular surface 18 of the table. When, however, a bottle is encountered which is longer than usual, which is often the case because of the crude way in which such bottles are made, the stroke of the capping head remaining the same as before, the table 16 must yield sufficiently to compensate for the extra length of bottle, or otherwise the bottle will be broken. Therefore, the spring 30 is constructed to yield slightly when this abnormal pressure upon the table is exerted, and, when the table travels downward, its inclined surface 18 strikes the rollers 28 and forces them inward, thus throwing outward the lower ends of levers 27 into the notches

22 of disk 20. This releases the supporting disk 23 and leaves the table 16 supported only by the spring 24 which, being comparatively weak, permits the table to recede and relieve the bottle from the extraordinary pressure of the machine. The bottle is, nevertheless, capped as effectually as a bottle of ordinary length and, after the return stroke of the machine, the bottle is removed and another replaced without any disturbance of the operation. On the return stroke, the spring 24 lifts the disk 23 to its normal position, the levers 27 being carried with it until their lower ends clear the top of the disk 20, when their springs 29 force them inward to rest upon the top of disk 20. Spring 30 meanwhile resumes its normal position, carrying the table to its proper normal working level.

It will be seen that the levers act as latches to sustain the abutment disk 23 at its proper working level, and, when they are tripped, the abutment is released and a second and weaker spring is substituted to support the table. The springs are originally constructed to be of the right power to do the work, but, any weakening or strengthening of them which may be required is accomplished by the adjusting screw 14.

What I claim is:

1. In a bottle capping machine, a depressible table, a spring for resisting depression of the table, an abutment for said spring, means for positively and rigidly locking said abutment against depression, and means actuated by more than a predetermined depression of said table for releasing the locking means for said abutment and permitting the latter to retreat.

2. In a bottle capping machine, a depressible table, a spring for resisting the depression of said table, an abutment for said spring, a latch for positively and rigidly locking said abutment against depression, and means actuated by more than a predetermined depression of said table for releasing said latch.

In witness whereof, I subscribe my signature, in the presence of two witnesses.

GEORG KIRKEGAARD.
